UNITED STATES PATENT OFFICE.

THOMAS RUSSELL HAYTON, OF QUINCY, ILLINOIS.

CENTRIFUGAL PUMP.

1,032,828.

Specification of Letters Patent. Patented July 16, 1912.

Application filed July 8, 1911. Serial No. 637,486.

To all whom it may concern:

Be it known that I, THOMAS RUSSELL HAYTON, a citizen of the United States, residing in Quincy, in the county of Adams 5 and State of Illinois, have invented new and useful Improvements in Centrifugal Pumps, of which the following is a specification.

This invention relates to centrifugal 10 pumps of the type employing double runners or impellers, and the object of the invention is to provide a novel construction and organization of parts whereby a pump will be provided which will yield a very 15 high efficiency in operation.

To this end the invention resides briefly in providing a casing with two suction or inlet openings, and the ordinary volute terminating in a discharge opening, and in locating 20 within the casing a central relatively small impeller, the function of which is to impart the initial speed to the water, and also to discharge the water therefrom at practically the speed it will have when passing into the 25 volute. Surrounding the impeller is located a rotary member with blades located a suitable distance beyond the impeller and terminating short of the periphery of the rotary member, the impeller and the rotary member 30 being mounted on different shafts and separately rotated from different pulleys, the speed of rotation of the rotary member being such that in practice it will neither retard nor accelerate the speed of the water 35 acquired from the impeller. Arrangements are likewise provided for maintaining an air-cushion between the sides of the rotary member and the wall of the casing and to prevent the air from leaking through the 40 bearings at the center by means of a water seal, the supply of air and water for these purposes being automatically provided in the operation of the pump. The blades of the rotary member are provided largely as 45 supports or braces to prevent the walls of the said member from caving in under the high pressure to which they are subjected. This and other details of construction, however, will more clearly appear from the 50 description to follow.

In the accompanying drawings—Figure 1 is a view in side elevation of a pump constructed according to my invention; Fig. 2 is a longitudinal sectional view of the same 55 on an enlarged scale; and Fig. 3 is a cross sectional view.

Referring now to the drawings, 1 indicates the casing providing a volute 2, terminating in a discharge spout 3. Extending into the casing from one side thereof is a 60 hollow shaft 4 mounted in suitable bearings 5, and driven by a pulley 6. Extending into the casing from the opposite side from that described is a smaller shaft 7, having its inner end mounted in the shaft 4, and driven 65 independently from the latter shaft by means of a pulley 8. Suitable bearings 9 are provided for the shaft 7. The casing 1 provides two suction openings 10.

11 indicates, generally, the impeller, the 70 blades 12 of which are suitably supported at their center by means of a circular plate 13 mounted on a hub 14, which, in turn, is secured to the shaft 7. At their outer ends the blades 12 are secured to annular rings 75 15, which rings have a stepped bearing indicated at 16, on a similar annular ring 17 which forms a part of the rotary member. The annular rings 17 have two stepped bearings on their outer side in the wall of the 80 casing 1, as indicated at 18 and 19, these bearings being separated by small annular spaces 20 with which connect water channels 21 extending from the volute 2 to the spaces 20. These water channels are shown as being 85 provided in opposite walls of the casing itself, but other means, such as pipes, could obviously be provided for connecting the volute with the central bearing of the impeller. The channels 21 are provided at intervals 90 around the entire casing of the pump, and extend radially from the volute 2 to the annular spaces 20.

22 indicates a hollow, rotary member, the 95 walls 23 of which are connected at their center to the annular rings 17, as indicated at 24. The sides of the rotary member converge toward the periphery, and the inclination is such as to make the areas of successive annular cross sections of the rotary 100 member equal; thus compensating for the increase in volume of a circular chamber toward the periphery so that the rotary member will run full of water fed by the central impeller. A further object subserved 105 by converging the walls of the rotary member is to give additional resistance to pressure from the outside.

25 indicate hubs, one of which is secured 110 on the shaft 4, and the other of which is loosely mounted on the shaft 7, between which hubs and the annular rings 17 are

mounted inclined blades 26, which are intended primarily as supports connecting the hubs 25 with the rotary member, but as they rotate in the central openings through which water passes into the center of the impeller from the suction openings 10 they are so inclined as that in rotation they will not impede the progress of the water, although it is not intended that they should materially accelerate the speed of the water passing into the impeller.

Extending between the walls 23 of the rotary member are a circular series of blades 27, the shape of which is more clearly shown in Fig. 3. As will be seen, these blades are substantially V-shaped, except that their walls are on curved lines, and the end of one blade enters a slight distance in the opening of the adjacent blade. As heretofore stated, the blades 27 are primarily intended as supports for the walls 23 of the rotary member, and the particular shape adopted I deem best calculated to provide the firm support necessary without thereby offering any hindrance to the free passage of the water to the volute 2 under the speed acquired from the impeller 11. In practice the rotary member 22 is run at such speed that the center of the blades 27, which is the pointed portion indicated by 28, will have the same speed of rotation as the peripheral speed of the impeller 11. Between the periphery of the impeller and the lower portion of the blades 27 there is provided a free annular space 29, and the water rotating under its own momentum in this space will have, therefore, a greater speed of rotation than the lower portions 30 of the blades 27, hence this water can readily pass through into the spaces 31 between the respective blades without diminution of its speed. As the water enters the space 32 opposite the end of each blade and inclosed by the adjacent blade it will be acted on by the upper members 33 of the blades as it passes out of the spaces 34, and in case the water has lagged a little in speed it will be speeded up by the blades. I wish it to be distinctly understood, however, that the form of blade described is that which at present I conceive to be the best form to support the walls of the rotary member without impeding the speed of the water. Other forms of blade might answer just as well, as I do not desire the rotary member to accelerate the speed of the water to any material extent over that imparted to it by the impeller, the function of the rotary member being to prevent, by its rotation, frictional resistance being offered to the water as it passes under the speed imparted to it by the impeller, and by centrifugal force through the rotary member and into the volute 2. Between the blades 27 and the periphery of the rotary member there is

an annular space 35 provided. That is to say, the blades 27 do not extend out to the periphery of the rotary member. By the provision of the space 29 between the impeller and the blades 27, and the space 35 between the blades 27 and the periphery of the rotary member I provide for utilizing the centrifugal force of the water under the speed imparted to it by the impeller without expending any further power upon the water, the full centrifugal force of the water being thus conserved, and as this water under the action of centrifugal force is moving against the walls of the rotary member, which themselves are moving at substantially the same rate of speed, there is practically no resistance offered to the free course of the water from the time it leaves the impeller until it passes out into the volute of the pump.

In order to provide for the access of air to the spaces 36 between the sides of the rotary member and the opposite sides of the casing, one or both suction inlets 10 is provided with an air inlet valve 37 so that air may be drawn in with the water, and as it passes out with the water the tendency will be for the air to be drawn back into the spaces 36 around the periphery of the rotary member. As it is possible, however, that a sufficient amount of air may not pass into the spaces 36 I provide for this emergency by mounting on the discharge pipe 38 an air dome 39 communicating with the interior of said pipe, so that as air passes out with the water it will be trapped in the air dome 39. From the top of the air dome 39 leads a pipe 40 which is connected through a valve 41 with pipes 42 which lead through opposite sides of the casing of the pump and communicate with the spaces 36. By this means the spaces 36 will be continuously provided with air and thereby prevent water from passing into these spaces, the presence of the water offering considerable resistance to the movement of the rotary member. Owing to the enormous suction at the center of the pump and the pressure at the periphery of the rotary member the air will not remain in the spaces 36, but will pass out at the bearings at the center of the pump unless its escape is prevented. To provide for sealing the air in the spaces 36 I provide the water channels 21, heretofore described, through which water under the enormous pressure in the volute will be forced into the annular spaces 20, and as this pressure is continuous there will be an annular wall of water under great pressure interposed between the stepped bearings 19 and the stepped bearings 20, which will prevent air from escaping through the latter to the center of the pump where its presence will be exceedingly detrimental. I provide an annular channel or throat 43, connecting

the working chamber of the rotary member with the volute, to insure a greater pressure of water in the volute, and therefore at the water seal, than at the periphery of the 5 larger impeller.

The operation of the pump has been included in the foregoing description, and it needs only to add that in the operation of a 10 pump constructed and organized as described a much higher efficiency can be obtained than with any other form of centrifugal pump of which I am aware.

I claim:

1. In a centrifugal pump the combination 15 with a pump casing of a rotary impeller located therein, a hollow rotary member encircling and immediately adjacent to said impeller and forming a chamber in communication with the casing into which said 20 impeller immediately delivers, said member comprising side walls suitably supported in position to constitute such chamber and being free from obstructions in the portion of the chamber adjacent to the impeller, and 25 means for independently rotating said impeller and rotary member in the same direction.

2. In a centrifugal pump the combination 30 with a pump casing of a rotary impeller located therein, a hollow rotary member encircling and immediately adjacent to said impeller and forming a chamber in communication with the casing into which said 35 impeller immediately delivers, said member comprising side walls and supports connecting them which are placed at a distance from the impeller, and means for independently rotating said impeller and rotary member in the same direction.

40 3. In a centrifugal pump the combination with a pump casing of a rotary impeller located therein, a hollow member encircling and immediately adjacent to said impeller and forming a chamber in communication 45 with the casing into which said impeller immediately delivers, said member comprising side walls and supports connecting them which are placed at a distance from the impeller and from the periphery of the rotary 50 member, and means for independently rotating said impeller and rotary member in the same direction.

4. In a centrifugal pump, in combination 55 with a pump casing having a volute, a rotary member mounted in the casing having a running-joint connection therewith and operating to discharge water into said volute, the construction affording air spaces between the walls of said member and the 60 walls of the casing, means for admitting air to said spaces, a water seal surrounding each of said running-joints, conduits connecting said water seals and the volute, whereby water will be continuously supplied to and 65 maintained under pressure in said water

seals to prevent the escape of air through the said running-joints, and means for rotating said member.

5. In a centrifugal pump, in combination with a central impeller, a hollow rotary member 70 encircling and immediately adjacent to the same, said member comprising side walls and supports connecting them which are located at a distance from the impeller and from the periphery of the rotary member, the construction affording air spaces between the walls of said member and the walls of the casing, means for admitting air to said spaces, water seals surrounding the bearings of the rotary member, conduits connecting said water seals and the volute whereby water will be supplied to and continuously maintained under pressure in said water seals to prevent the escape of air through the bearings, and means for 75 independently rotating said impeller and rotary member in the same direction.

6. In a centrifugal pump, in combination with the pump casing having a volute, a hollow rotary member mounted in the casing and operating to discharge water into said volute, the construction affording air spaces between the walls of said member and the walls of the casing, and means for automatically collecting air passing through 80 the pump and conducting it to said spaces.

7. In a centrifugal pump, in combination with the pump casing having a volute, a hollow rotary member mounted in the casing and having a running-joint connection 85 on opposite sides therewith, and operating to discharge water into said volute, the construction affording air spaces between the walls of said member and the walls of the casing which terminate at their base in said 90 running-joints, water seals encircling the said running-joints, means for automatically collecting air passing through the pump and conducting it to said spaces, and means for automatically maintaining a supply of 95 water in said water seals under pressure, whereby to prevent the escape of air from said spaces through said running-joints.

8. In a centrifugal pump in combination with a central impeller, a rotary member 100 surrounding the impeller, the construction providing spaces between the walls of said member and the walls of the casing, a water seal surrounding the bearings of the rotary member, water channels leading from 105 the volute of the pump to said water seals, an air chamber communicating with the outlet pipe of the pump, pipes communicating with said chamber and said spaces, respectively, and means for independently driving said 110 rotary member and said impeller.

9. In a centrifugal pump, in combination 115 with the pump casing, a rotary member mounted therein, the construction affording unoccupied spaces between the wall of said 120

member and the wall of the casing, a water seal surrounding the bearing of said member, water channels leading from the volute of the pump to said water seals, and means for automatically collecting air passing through the pump and supplying it to said spaces.

In testimony whereof, I have hereunto set my hand in presence of two subscribing witnesses.

THOMAS RUSSELL HAYTON.
